UNITED STATES PATENT OFFICE.

WILLIAM M. TAYLOR AND IRA P. MERRILL, OF PARSONS, KANSAS; SAID MERRILL ASSIGNOR TO SAID TAYLOR.

CHURN.

SPECIFICATION forming part of Letters Patent No. 289,786, dated December 4, 1883.
Application filed June 21, 1883. (No model.)

To all whom it may concern:

Be it known that we, WILLIAM M. TAYLOR and IRA P. MERRILL, of Parsons, in the county of Labette and State of Kansas, have 5 invented certain new and useful Improvements in Churns; and we do hereby declare that the following is a full, clear, and exact description of the invention, which will enable others skilled in the art to which it applies to make and use the same, reference being had to the accompanying drawings, which form a part of this specification, and in which—

Figure 1 is a perspective view of our improved churn, the cover having been removed and part of the casing broken away. Fig. 2 is a perspective view of the rotary cylinder. Fig. 3 is a vertical longitudinal section, and Fig. 4 is a detail view of one of the 20 bearings.

Similar letters of reference indicate corresponding parts in all the figures.

Our invention has relation to churning adapted to be used also as washing-machines; 25 and it consists in the construction and combination of parts of the same, as hereinafter more fully described and claimed.

In the accompanying drawings, A is the outer casing or box, in one end of which is 30 fastened the bridge-piece B, which forms a bearing for the drive-shaft C. The latter has a crank, D, for turning it, and upon it is keyed or otherwise fastened the drive-wheel E, which meshes with the pinion F. In opposite ends of the box are arranged vertical cleats, forming ways (shown at G G) for the insertion of the removable bearings H H, one of which forms a bearing for the outer end of the drive-shaft C. By lifting the 35 bearings H out of their respective ways G, and removing the bridge-piece B, the inside cylinder, with its driving-gear and other appurtenances, may be removed from the box. This inside cylinder, consists of two heads, I, 40 of circular shape, and slotted, as shown at J, the wings K, formed by said slots, being bent in an outward direction, so as to form outwardly-flaring blades, as will appear more clearly by reference to Fig. 2 of the draw-

ings. The heads I I are connected by slender 50 rods or wires L, and the cylinder is provided with a hinged door, by means of which access may readily be had to the inside. When in use, the box or casing A is covered by an arched cover N.

From the foregoing description, taken in connection with the drawings, the use and operation of our combined churn and washing-machine will readily be understood. When used as a churn, the cream is placed in the 60 box, after which the cover is placed in position, and by turning the crank the inside cylinder is made to revolve rapidly, thus effectually stirring and breaking the cream. As the outwardly-flaring wings or blades K cut 65 through the cream, this is forced into the cylinder from opposite directions, as indicated by the arrows, thus forming currents, which meet in the center of the cylinder and effectually break up the bulk or body of the 70 cream, which causes the butter-globules to form or "come" very rapidly. The butter, when formed, can readily be taken out of the box by removing the cylinder and its driving-gear, which, as already stated, is done by 75 lifting the bearings H out of their respective ways.

When the apparatus is to be used as a washing-machine, the articles to be washed are placed inside of the cylinder through the 80 door, and the box is partially filled with hot water and suds, after which the cover is placed in position. The cylinder is then rotated as before, which will force the hot suds into the cylinder from opposite directions, causing 85 them to thoroughly permeate the clothes, and effectually remove all dirt, after which they are rinsed out in the usual manner.

We are aware that churning have been made before consisting of a horizontal slatted cylinder revolving in a box or casing, and we do not wish to claim such construction, broadly; but

What we claim, and desire to secure by Letters Patent of the United States, is—

The combined churn and washing-machine herein shown and described, composed of the box or casing A, having ways G G at opposite

ends, and provided with an arched cover, N, removable bridge-piece B, bearings H H, driving-gear composed of the crank D, shaft C, cog-wheel E, and pinion F, and rotary cylinder L I, constructed with the slats or apertures J and outwardly-flaring wings K, the whole constructed and combined substantially as and for the purpose herein shown and specified.

In testimony that we claim the foregoing as to our own we have hereunto affixed our signatures in presence of two witnesses.

WILLIAM M. TAYLOR.
IRA P. MERRILL.
